(57) **CLAIM**

The ornamental design for a bottle, as shown and described.

DESCRIPTION

FIG. 1 is a front elevation view of a bottle showing my new design;

FIG. 2 is a 3/4 perspective view thereof;

FIG. 3 is a rear elevation view thereof;

FIG. 4 is a 3/4 perspective view thereof;

FIG. 5 is a top plan view thereof;

FIG. 6 is a bottom plan view thereof;

FIG. 7 is a left-side elevation view thereof; and,

FIG. 8 is a right-side elevation view thereof.

The broken lines depict portions of the bottle that form no part of the claim.
